UNITED STATES PATENT OFFICE.

HENRY G. SCHMIDT, OF NORWALK, CONNECTICUT, ASSIGNOR TO THE NORWALK TIRE & RUBBER COMPANY, OF NORWALK, CONNECTICUT, A CORPORATION OF CONNECTICUT.

DESIGN FOR A TIRE.

Application filed March 15, 1922. Serial No. 1,178. Term of patent 3½ years.

To all whom it may concern:

Be it known that I, HENRY G. SCHMIDT, a citizen of the United States, residing in the city of Norwalk, county of Fairfield, and State of Connecticut, have invented a new, original, and ornamental Design for a Tire, of which the following is a specification, drawing, forming a part thereof.

In the drawings Figure 1 is a top plan view of a tire section embodying my design; Figure 2 is a cross-section of Figure 1 on the line 2—2, but with the lower ends broken away for convenience in illustration.

I claim:

The ornamental design for a tire, as reference being had to the accompanying shown.

HENRY G. SCHMIDT.
